Primary Examiner—Catherine Tuttle(74) *Attorney, Agent, or Firm*—Cislo & Thomas, LLP(57) **CLAIM**

I claim the ornamental design for a whimsical flamingo spinner, as shown and described.

DESCRIPTION

FIG. 1 is a front view of my whimsical flamingo spinner; FIG. 2 is a rear view thereof; FIG. 3 is a left side elevational view thereof with the right side elevational view being a mirror image; and FIG. 4 is a top view thereof. The broken lines are included for the purpose of illustrating portions of the article that form no part of the claimed design.
